INVENTOR

JOHN A. LIPPERT

By W. T. Miller
ATTORNEY.

UNITED STATES PATENT OFFICE.

JOHN A. LIPPERT, OF BUFFALO, NEW YORK.

METAL RAILWAY-TIE.

No. 797,296.

Specification of Letters Patent.

Patented Aug. 15, 1905.

Application filed April 10, 1905. Serial No. 254,852.

To all whom it may concern:

Be it known that I, JOHN A. LIPPERT, a citizen of the United States, residing at Buffalo, in the county of Erie and State of New York, have invented certain new and useful Improvements in Metal Railway-Ties; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

My invention relates to improvements in metal railway-ties, its object being to provide a construction which will involve a minimum of material and which will at the same time possess the requisite structural rigidity, provision at the same time being made in such construction whereby the tamping of the tie in the road-bed is rendered both expeditious and effective and a center-bound track is entirely avoided.

To these ends my invention consists of a tie having a top bearing-plate upon which the track-rails rest and are secured, a bottom base-plate, a vertical web connecting the bearing-plate and base-plate, centrally-arranged between the same, and oppositely-arranged strengthening and guiding wings extending up from each end of the base-plate.

My invention further consists of a tie having a top bearing-plate upon which the track-rails rest and are secured, such bearing-plate having a narrowed central portion, a bottom base-plate having a narrowed central portion, and a vertical web connecting the bearing-plate and base-plate, centrally arranged between the same.

In the drawings, Figure 1 is a perspective view of my improved tie. Fig. 2 is an under side view of the same, and Fig. 3 is a vertical transverse section taken in the line *x x* of Fig. 1.

Referring to the drawings, 1 is the top bearing-plate, upon which the track-rails rest and are secured. This plate has the narrowed central section 2.

3 is the base-plate, having the narrowed central section 4.

5 5 5 are four wings upturned from the base-plate 3 on opposite sides and at each end of the same.

6 is the vertical web connecting the bearing-plate 1 and the base-plate 3, being cen-

trally arranged between and integral with the same.

The entire tie is rolled from one piece of metal, the wings 5 being turned up and the central sections of the bearing-plate and base-plate being narrowed by cutting away portions of the same.

The functions of the wings 5 are twofold. First, they strengthen the tie directly under the points of greatest pressure, and, second, they serve as guides to direct the tamping-tool under the tie, and thus greatly expedite the tamping operation.

The function of the narrowed central portions 2 and 4 of the bearing-plate and base-plate is that it prevents a center-bound track, which now occurs with ties either of wood or metal which have their bases of uniform width throughout their entire length. It often happens that the road-bed under the ends of the tie becomes loosened from frequent pounding, and the weight of the passing train causes the ends of the tie to bend down while the center of the tie remains rigid, which often results in the breaking of the tie at its center, as has been frequently demonstrated in the use of wooden ties. This objection is overcome with my improved feature of narrowing the central portions of the tie, which enables such portions to be forced down into the road-bed uniformly with the sinking of the ends, thereby avoiding any unequal strains upon the tie throughout its entire length and preventing what is commonly known as a "center-bound track."

I claim—

1. A metal railway-tie having a top bearing-plate upon which the track-rails rest and are secured, a bottom base-plate, a vertical web connecting the bearing-plate and base-plate, centrally arranged between the same and oppositely-arranged strengthening and guiding wings extending up from each end of the base-plate.

2. A metal railway-tie having a top bearing-plate upon which the track-rails rest and are secured, such bearing-plate having a narrowed central portion, a bottom base-plate having a narrowed central portion and a vertical web connecting the bearing-plate and base-plate, centrally arranged between the same.

3. A metal railway-tie having a top bearing-plate upon which the track-rails rest and are secured, such bearing-plate having a nar-

rowed central portion, a bottom base-plate having a narrowed central portion, a vertical web connecting the bearing-plate and base-plate, centrally arranged between the same and oppositely-arranged strengthening and guiding wings extending up from each end of the base-plate.

In testimony whereof I have signed my name to this specification in the presence of two subscribing witnesses.

JOHN A. LIPPERT.
